GARMENT BAG APPLYING AND
REMOVING DEVICE

Willie A. Shields, Powderly, Ala.

Application December 22, 1945, Serial No. 636,782

2 Claims. (Cl. 226—18)

1

This invention relates to an electric power operated device for applying and removing the paper bags used to protect cleaned and laundered garments. This invention is an improvement over the device shown in my previous United States Patent Number 1,304,913, dated May 27, 1919.

The main object of the invention is to provide means for quick handling of garment protecting paper bags that are commonly used in dry cleaning establishments and laundries so that they can be easily applied over the garment or removed therefrom when it is desired to inspect the garment. Garments to be inclosed within the paper bags are of different lengths, so bags of corresponding lengths are used. The present invention is adapted to handle easily and quickly the various lengths of bags.

Other advantages will appear from the drawings and description.

By referring to the drawings in general, that are part of this application, it will be observed that Fig. 1 is a back elevational (broken) view of the device, part on line 1—1 of Fig. 4, with garment hanger on bottom hook; Fig. 2 is a vertical sectional (broken) view of the device on line 2—2 of Fig. 1; Fig. 3 is a sectional view on line 3—3 of Fig. 1; Fig. 4 is a sectional view on line 4—4 of Fig. 5 showing the operating mechanism of the device; Fig. 5 is a partial view on line 5—5 of Fig. 4 showing other part of operating mechanism on the front of the device; Fig. 6 is a sectional view on line 6—6 of Fig. 5; and Fig. 7 is a sectional view on line 7—7 of Fig. 1 partly broken away.

Similar reference numerals refer to similar parts throughout the several views.

Referring to the drawings in detail it will be seen that the device comprises a panel case or box with a front 1 and a back 2 carried by the lower portions or ends of channel sides 3 that are attached to a cross top member 4 that is supported by a piece of pipe that fits into a regular pipe sleeve 6. A center long rod 5 is attached to the pipe and extends down through the panel case or box and forms a hook 11 at its end. A pipe 7 of any desired length is attached to a screw socket base fastened to the operating room ceiling 10. To make minor adjustments of the hanging position the top supporting parts are provided with a slot 8 in the upper piece of pipe 7, and a set screw 9 to hold parts in fixed position.

The device is operated by a small electric motor 12 that is attached to the back of the panel case. A pulley 13 on the motor shaft drives

2

through a belt 15 a larger pulley 14 mounted on a countershaft 19 supported in journals 24 attached to the case panel. A small pulley 16 is mounted on the countershaft 19 and drives through a belt 18 another pulley 17 that is carried on another shaft 20 supported in bearings 25 attached to the case panel. The countershaft may be used with a sufficiently slow revolving motor. On each end of the shaft 20 there is a roller 22 made with a soft periphery, preferably rubber, that is attached to and revolves with the shaft 20. These rollers 22 partly extend through windows or openings 36 in the panel 1. On the opposite panel face 2 of the case the operator's controls are placed. They consist of a rocker arm 26 mounted centrally on a short shaft 32 supported in a base 27 that is attached to the panel 2. A spring 28 is inserted between one end of the rocker arm 26 and the face of the panel 20 and is disposed to urge the arm end away from the panel face. The other end of the rocker arm carries an attached shaft 21 with a free revolving roller 23 on each end. These rollers are of the same size and material as the other driving rollers 22. When the rocker arm is set as shown plainly in Fig. 4 the sets of rollers face and contact each other in pairs. To overcome the spring tension a crank lever 30 is mounted in a bearing housing 29 that is attached to the panel face. The crank lever 30 is provided with an operating handle 33 at one end, and also has at its other end a small roller 30'. By shifting the crank lever 30 the rocker arm is tilted as shown by dotted lines in Fig. 4 and the little roller on the end of the crank lever 30 fits into a notch 31 in the rocker arm, thus overcoming the expansion urge of the spring 28 and holding the rollers on the shaft of the rocker arm away from the other driving rollers as shown by the dotted lines in Fig. 4. The panel face 2 also has windows or openings 36 adapted for parts of the rollers on the rocker arm shaft to make contact with the driving rollers. Suitable weak springs 35 are placed beside the edges of the driving rollers 22 to hold the lower edge of the bag 37 off the driving rollers when the bag is all the way up in the device. The top of the panel case is provided with flare guides 34, and its bottom opening is also flared. A paper bag 37 is shown up in the device, and also is shown in dotted lines of its top portion as it starts up into the device. The electric motor is provided with necessary supply wires 40 leading from a regular control switch 38 with an operating handle 39. An ordinary wire coat hanger 41 is shown hanging on the hook 11.

From the foregoing it will appear that to use the device the rollers are set in the position shown by the regular lines in Fig. 4, then the motor is started causing the rollers to revolve face to face driving upward between their contact faces. Then a regular type of garment bag with hanger opening in its top edge is inserted into the lower opening of the panel case with the long hanger rod through the top opening of the bag. As the upper end of the bag comes into contact with the revolving driving rollers it is carried upward until its bottom edge clears the driving rollers and is held off the rollers by the shielding springs. The side edges of the bag travel upward in the channel sides of the device and are there held in line. Then a regular suit hanger with a suit or dress thereon is placed upon the end hook of the long center shaft. In this position the rocker arm shaft rollers are tilted away from the driving rollers as shown by the dotted lines in Fig. 4, allowing the bag to slide or be pulled downward and over the suit or dress on the hanger suspended on the hook of the long center rod, thus finishing the operation of applying the bag over the garment. To remove the bag if desired for inspection of the garment, it is lifted by its top edge from the garment and started upward through the rollers in the same manner as previously for applying over the garment.

The various parts of the device may be made from any material best suited for the purpose.

While I have shown and described the preferred embodiment of my invention, I do not wish to limit same to the exact and precise details of structure, but reserve the right to make all modifications and changes so long as I remain within the spirit and scope of the following claims.

Having described my invention I claim:

1. A garment bag applying and removing device comprising; an adjustable connection for attaching to a ceiling, a frame attached to the lower end of the adjustable connection, the side members of the frame forming channels, a panelled case supported in the lower portion of the frame, an electric motor mounted on one outer face of the case, two driving rollers mounted on and adapted to revolve with a shaft supported in bearings attached to the outer face of the case, pulley and belt means leading from the motor to the shaft with said rollers and adapted to revolve the rollers, slots cut through the outer panel face, the rollers positioned with part of each protruding through a slot; a rocker arm mounted in a supporting bearing attached to the opposite outer face of the case, a spring positioned between one end of the rocker arm and the opposite face of the case and adapted to urge the end of the arm away from the case, a shaft attached to the other end of the rocker arm, a free revolving roller mounted on each end of the arm shaft, slots cut through this opposite face substantially the same size as the slots in the other panel face, parts of the arm shaft rollers adapted to protrude through the slots and make contact with the driving rollers protruding through the opposite panel, a crank type lever mounted on the opposite face of the panel and adjacent the rocker arm and adapted by manual operation to overcome the spring urge and lift and hold the arm shaft and free revolving rollers away from the opposite driving rollers; a long depending rod with its upper end attached to the top of the frame and extending down through and beyond the panel case bottom edge, a hook integral with the bottom end of the long rod and adapted for a garment hanger to be supported thereon; weak springs positioned within the panel case and attached adjacent the sides of the driving rollers and adapted to act as resisting shields to hold a paper bag when descending in the device, off of the face of the driving rollers; flared edges integral with the top and bottom edges of the panel case.

the panel case bottom edge, a hook integral with the bottom end of the long rod adapted for a garment hanger to hang thereon; weak springs positioned within the panel case and adjacent the sides of the driving rollers and adapted to act as resisting shields to hold a bag when descending off of the face of the driving rollers.

2. A device of the character described comprising; an adjustable pipe connection with a base for attaching to a room ceiling, an elongated frame attached to and suspended on the lower end of the pipe connection, the side members of the frame forming channels adapted for the edges of paper bags to slide therein, a panelled case supported in the lower portion of the frame, an electric motor mounted on one outer face of the case designated as the back of the case, electric switch means adjacent the motor for operation thereof, two driving rollers mounted on the ends of a shaft and adapted to revolve with the shaft that is supported in bearings attached to the face of the outer case, pulley and belt means leading from the motor to the shaft with said rollers thereon and adapted to drive the shaft and rollers, slots cut through the panel face, the said driving rollers positioned with part of each protruding through a slot; a rocker arm mounted in a supporting bearing attached to the opposite outer face of the case and designated as the front thereof, a spring positioned between one end of the rocker arm and the face of the case and adapted to urge the end of the arm away from the case and the other end of the arm toward the case, a shaft attached centrally and at right angle to the end of the rocker arm opposite the spring operated end, a free revolving roller mounted on each end of the arm shaft, slots cut through this face substantially the same size as the slots in the opposite panel face, parts of the arm shaft free rollers adapted to protrude through the adjacent slots and make contact with the driving rollers protruding through the opposite panel face, a crank type lever with a small roller on one end mounted on the face of the panel and adjacent the rocker arm end opposite the spring end and adapted by manual operation to overcome the spring urge and lift and hold the arm shaft and free revolving rollers away from contact with the opposite driving rollers; a long depending rod with its upper end attached to the top of the frame and extending down through and beyond the panel case bottom edge, a hook integral with the bottom end of the long rod and adapted for a garment hanger to be supported thereon; weak springs positioned within the panel case and attached adjacent the sides of the driving rollers and adapted to act as resisting shields to hold a paper bag when descending in the device, off of the face of the driving rollers; flared edges integral with the top and bottom edges of the panel case.
